UNITED STATES PATENT OFFICE.

THOMAS HENRY RANDOLPH, OF LONDON, ENGLAND.

SAFETY-RAZOR-STROPPING DEVICE.

No. 895,498.

Specification of Letters Patent. Patented Aug. 11, 1908.

Application filed July 19, 1907. Serial No. 334,613.

To all whom it may concern:

Be it known that I, THOMAS HENRY RANDOLPH, a subject of the King of England, residing at London, England, have invented 5 certain new and useful Improvements in Safety-Razor-Stropping Devices, of which the following is a specification.

This invention relates to improvements in safety razor stropping devices of the type in which the relative position of the blade and the strop is altered automatically at the end of each stroke by means of one or more lateral rollers each carrying a toothed segment engaging with a toothed pinion on the rotatable 15 blade-support.

One object of this invention is to enable two cutting edges to be stropped at one operation and another object is to strop a double-edged razor blade on both cutting 20 edges without removing the blade from the device.

The invention is particularly suitable for stropping the thin double-edge blades used in certain safety razors.

According to this invention, a frame having a handle at either end carries a blade-support journaled on its longitudinal axis and having a toothed pinion at one end. Rollers are arranged parallel with and close to either 25 edge of the blade and each roller has a toothed segment engaging the pinion. The machine is placed so that it rests with its rollers on a strop and by means of the handles is passed to and fro over the strop (or vice versa). By turning the device over so that the blade-holder is reversed the remaining faces can be sharpened, the whole operation being performed without removing the 30 blade from its support.

In an alternative form a single roller may be arranged parallel with and close to one edge of the blade and having a toothed segment engaging the pinion, and a flexible strop may be passed to and fro over the roller 40 so that the two sides of one cutting edge are alternately brought into contact with the strop as it is pulled to and fro.

The blade-support according to this invention comprises one plate attached to the 45 journals or pivot pins at the ends and a second plate hinged thereto at one end. Either plate, say the first, may be provided with projections to engage slots in the thin blade so as to determine its position, and the 50 hinged plate may be folded down on to the blade and held in place by a screw or by

a spring or other catch. If desired, the hinged plate may be spring-controlled so that when the screw or catch is released the support springs open and releases the blade 55 quickly.

One form of stropping device for thin double-edged safety-razor blades embodying this invention is illustrated in the accompanying drawings.

Figure 1 is a perspective view of the complete machine as used according to one method. Fig. 2 is a detail view of the blade-support, and Fig. 3 is a diagrammatic illustration of a second method of using the machine.

Like letters indicate like parts throughout the drawings.

Between two side plates K a blade-support C is pivoted on its longitudinal axis. 75 The support C comprises one plate B having journals or pivot pins D at its ends and having projections E to engage the holes in a thin blade. A second plate A is hinged at one end F to plate B and is also provided 80 with holes corresponding with those in the blade, and the plate A can be folded down and secured to the plate B so as to grip the razor blade in the middle and leave the two cutting edges exposed. A convenient form 85 of catch for holding the plate A in its closed position consists of a screw H passing through the journal D at one end and arranged to engage a hole I in the end of the hinged plate A. The pivot pin D of the support at one end carries a toothed pinion J, 90 outside the side plate K. The plates A and B of the blade-support are made conveniently narrower than a razor blade. Journaled between the side plates K and parallel to the 95 blade-support C are two rollers L and M each of which carries a toothed segment N and O in engagement with the pinion J and the extent of the movement of these segments may be limited by stops P on the side plate K. 100 Beyond the rollers L rods R may be fixed between the side plates K and a handle or loop S may be attached to each end of the side plates.

There are various methods in which this device can be used. According to one method the device is placed so that it rests with its rollers L on the strop T. The operator by means of the handles S runs the machine to and fro along the strop T. With this arrangement one face of each cutting edge is alternately brought into contact with the 105

strop and sharpened in one operation, and to sharpen the two other faces on the opposite side of the blade it is only necessary to reverse the device that is to turn the machine over on the strop, the handles S being made to swing round accordingly.

It will be seen that there is another method of using this device as illustrated in the diagrammatic view shown in Fig. 3. According to this method the device is hung up by means of one of the handles S and the strop T is passed between the rod R and roller M nearest the handle on which the frame is supported. Both sides of the strop are then held taut and moved to and fro over the roller M so that opposite faces of each blade are sharpened simultaneously in each forward movement of the strop and also in each return movement thereof. According to this method of using the device only one of the rollers is utilized.

In another method of using the apparatus one end of the strop T is passed up between the roller L and the rod R and the other end 25 of the strop passed up between the roller O and the rod R. In this case the two faces of the opposite edges which lie on the same side of the blade are sharpened in one operation and to strop the remaining faces the device 30 is reversed and the strop is passed down over the other side of the rollers.

It is to be understood that the details of arrangement and construction may be varied without departing from this invention.

35 What I claim as my invention and desire to secure by Letters Patent is:—

1. In a device for stropping double-edged razor blades, the combination of a frame, a blade support journaled on its longitudinal axis in said frame and adapted to grip a double edged blade in the middle so as to leave the two cutting edges exposed, a roller rotatably journaled in said frame parallel with the blade holder, means for transmitting partial rotation from the roller to the blade-support, a strop, and means for caus-

ing the two opposite cutting edges of the blade to contact alternately with the strop on relative reciprocal movement of the frame and strop.

2. In a device for stropping double-edge razor blades the combination of a frame, a blade-support journaled on its longitudinal axis in said frame and adapted to grip a double-edged blade in the middle so as to leave the two cutting edges exposed, a toothed pinion at one end of said support, two rollers journaled in the frame parallel with and close to opposite sides of the blade support, a toothed segment on each roller engaging the said pinion and a strop which contacts with the rollers and alternately contacts with the opposite cutting edges of the blade on relative reciprocal movement of the frame and strop.

3. In a device for stropping double-edged razor blades, the combination of two side plates, distance rods connecting said plates, a blade-support comprising a main plate having pivot pins at its ends rotatably mounted in the side plates, projections on said main plate to engage holes in a double-edged razor blade, a retaining plate hinged at one end to said main plate and adapted to grip the razor blade in the middle and leave the two cutting edges exposed, a toothed pinion on one end of said support, two rollers journaled between the side plates and parallel with and close to the opposite sides of the blade-support, a toothed segment on each roller engaging the said pinion, and a strop which contacts with the rollers and alternately contacts with the opposite cutting edges of the blade on relative reciprocal movement of the frame and strop.

In testimony whereof I have signed my name to this specification in the presence of two subscribing witnesses:

THOMAS HENRY RANDOLPH.
